UNITED STATES PATENT OFFICE.

EDWIN J. HOUSTON, OF PHILADELPHIA, PENNSYLVANIA, ASSIGNOR TO
THE AMERICAN ELECTRIC COMPANY, OF NEW BRITAIN, CONN.

DYNAMO-ELECTRIC MACHINE.

SPECIFICATION forming part of Letters Patent No. 272,256, dated February 13, 1883.

Application filed December 5, 1881. (No model.)

To all whom it may concern:

Be it known that I, EDWIN J. HOUSTON, of the city and county of Philadelphia, State of Pennsylvania, have invented certain new and useful Improvements in Dynamo-Electric Machines, of which the following is such a description as will enable those skilled in the art appertaining thereto to make and use the same, reference being had to the accompanying drawings.

The objects of my invention are to secure greater ventilation by certain improvements in the construction of dynamo-electric machines, as well as to so improve the connection of the coils of the armature and the method of carrying off the currents at the commutator, so as to greatly increase the electro-motive force of the currents generated in the machine.

My invention relates especially, so far as the mode of connecting and carrying off the currents by the commutator are concerned, to machines of the Gramme and similar types, though it is to be understood that I do not limit myself to machines of this type, since I may, under certain circumstances, apply it as well to other types of machine.

In a practical system of electric lighting by the voltaic arc it is desirable, both on the score of convenience and economy, that a considerable number of lights be placed at suitable intervals in breaks in one and the same circuit—that is to say, that all the lights, or as many of them as possible, be placed in series. Where forty or more of these lights are placed in the same circuit a very high electro-motive force is required. One object of my invention is to readily obtain the requisite electro-motive force.

It is well known to those skilled in the art that in the Gramme and similar types of machine a difficulty is experienced in readily obtaining a high electro-motive force. This is caused by the fact that the mode of connecting the coils placed on the armature and the manner in which such currents are carried off at the commutator are such that the current traverses the coils on the armature in multiple arc. This results, as is well known, in a lowering of the resistance of the armature-coils, and a consequent decrease in the electro-mo-

tive force of the current generated therein. I propose to so combine the armature-coils with suitable circuit-closing or commutator devices for completing the connection between the successive coils as to cause the current generated in the armature-coils to pass through nearly all of said coils in series or for tension. By this means I obtain with the same length of wire a much higher electro-motive force than is practicable by the ordinary method of connecting the coils permanently to one another in endless series and joining the points of connection to the commutator-segments.

I will describe my invention first as it may be applied to a ring-armature wound with successive coils, as in the Gramme machine, but connected and carried off in the manner that I will now explain.

In Fig. 1 is shown a sketch of the Gramme ring mounted on a shaft, s , so as to be capable of rotation between the poles N and S . If X be taken as the neutral line, then a rotation of the ring in the direction of the large arrows $R^2 R^2$ will develop currents whose directions will be as indicated by the smaller arrows. Supposing the ring to be composed of separate coils, wrapped and connected in the usual manner, then brushes touching the sections of the commutator in positions corresponding to B and A would be the positive and negative terminals of the circuit through the armature—that is to say, the current would start at A , pass through all the wire on the armature in multiple arc, and emerge at B . According to my invention, however, the separate coils of the armature, instead of being connected to one another in series after the manner indicated in Fig. 1, (the outer end of each coil to the inner end of the next coil in succession proceeding in the direction of the arrows $R^2 R^2$), have their ends separately connected to the contact-points, terminals, or surfaces of suitable circuit-closing devices of such character as to complete the connection between the successive coils as they revolve in those portions of the field where current is generated, but to leave the contiguous ends of successive coils disconnected at the neutral points. As a break is thus caused to exist at or near the neutral points between the contiguous

uous coils, by suitably connecting those portions of the circuit-closing devices that are at the ends of each series of coils above and below the line passing through the neutral points, all the coils of the machine may be connected for tension, as will more clearly appear from the detailed description to be presently given. Under such a plan of connection there will obviously be twice as many pieces, points, or strips in the circuit-closing device or commutator as there are armature-coils.

Fig. 2 illustrates diagrammatically the principle of my invention, and also indicates one method of carrying the same into practice.

Fig. 3 is a perspective view of a portion of the circuit-closing device or commutator, and illustrates one of the constructions that may be employed.

Referring to Fig. 1, *a a a* &c., are supposed to represent separate commutator-plates, strips, pieces, segments, or surfaces, which are mounted on a cylinder, and insulated from one another thereupon by any suitable means known in the art. As indicated in Fig. 3, they are blocks of metal let into the edge of a disk or cylinder of insulating material mounted on the armature-shaft *s*, and separated from one another by the material of said disk.

C' C² C³ C⁴ C⁵, &c., indicate the twelve separate bobbins of a Gramme ring, the terminals of which are connected separately to the plates *a a a*, &c., in the manner indicated, while said plates are spaced, as shown, so that those plates to which the inner end of one bobbin and the outer end of the next successive bobbin are connected are nearer together than the two plates to which the inner and outer ends of any one bobbin are connected. The object of thus spacing the plates, pieces, or segments will be presently seen. The distances between the plates and the length of said plates is not material, provided the objects to be attained are secured. A series of commutator circuit-closing plates, springs, or brushes, *m m m*, &c., are applied to bear upon the plates *a a a*, &c., in such a way as to complete the connection between the inner and outer ends of the successive bobbins, *C' C² C³*, &c. These springs, or brushes may consist of a series of plates or springs mounted on any suitable support, and insulated from one another in any suitable manner, as indicated in Fig. 3. Each plate or brush *m* is of sufficient width to complete the connection between each pair of strips *a* to which the outer end of one bobbin and the inner end of the next contiguous bobbin in succession are connected, proceeding in the direction of the arrow *T*; but no brush *m* should be sufficiently wide to bridge the longer insulating-spaces between the two plates or strips *a a* to which the two ends of the same bobbin are connected, excepting at the terminals of the series of brushes or springs, as will be presently described, for the obvious reason that such connection would short-circuit the current generated in such bobbin. Two series

of brushes on opposite sides of the plates *a a*, &c., are employed, in order that there shall be no rupture of connection between the pairs of nearer plates *a* as the edge of a brush passes the insulating-space; and for this purpose the brushes on opposite sides should be made to break joint with one another, as indicated, a brush on one side bridging the joint between two brushes on the opposite side. As will be obvious, the width of each brush should be slightly greater than twice the width of the shorter insulating-space, in order that as a brush on one side is about to break connection between the pair of nearer plates *a a* the overlapping brush on the opposite side shall have advanced sufficiently far to complete the connection, and thus preserve the continuity of the connection.

In the above description it is assumed that the brushes move; but the principle is obviously the same as when the brushes are stationary and the plates *a a*, &c., move. With twelve coils, as indicated, the necessary conditions, as above explained, will be answered if each plate *a* cover six degrees of the circumference, each longer insulating-space fifteen degrees, each shorter insulating space three degrees, and each spring *m* nine degrees. These figures may be varied within the limits above prescribed. If the brushes *m* were extended around the entire circumference of the cylinder, the twelve bobbins would obviously be connected in endless series at all times during the revolution of the armature. In order, however, to provide for collecting the currents separately from the bobbins on the two halves of the armature above and below the neutral line *X X*, the plates *m m* are discontinued at and near this line, and provision made for preserving a connection with the same ends of the bobbins in succession as they approach or leave this line, so as to get a continuous current from the bobbins on both halves of the armature. This provision consists, in substance, in widening the terminal brushes *m* of each set above and below the neutral line to a sufficient extent to preserve a connection between each pair of plates separated by the longer insulating-spaces, and thus in effect, through the shorter brushes *m m*, contiguous to the widened brush, keep up a constant connection with the same ends of the successive bobbins, so as to prevent a break in the current collected. The collecting-brush to be thus formed may be made up of a single brush *m*, sufficiently widened, or of two overlapping brushes *m* on opposite sides of the commutator-cylinder electrically connected, one of said brushes being sufficiently widened to give to the two combined the requisite collecting width. The latter is the plan here indicated. Thus brush *P²* and the overlapping brush *m*, to which it is electrically connected by a wire, as indicated, or by any other suitable means, cover sufficient space on the cylinder to bridge the longer insulating-spaces. If the coils revolve in the direction of the larger

arrow and the currents circulate in the coils in the direction of the dotted arrows W , it is obvious that in order to obtain a continuous current from a collecting-brush, as $P^2 m$, connection 5 must be preserved by said brush with the outer ends of the successive bobbins above the neutral line, connection with one being made before connection with the preceding one is broken. This is accomplished by making the brush sufficiently wide to itself be always in connection either with a plate, a , connected to a forward or outer end of a bobbin or a plate connected to the rear or inner end of a bobbin. So long as it is in connection with the forward end of one 15 bobbin—say C^3 —it is obviously in condition to collect the current from the whole series of bobbins $C^3 C^2 C' C^{12} C^{11} C^{10}$, while if it make connection with the plate a connected to inner end of C before it breaks connection with 20 the outer end, it is in condition to still collect the current from the bobbins above the neutral line, it being then in connection with the outer end of the bobbin C^2 through the plate a connected to the inner end of C^3 , the contiguous brush or brushes m , which preserve the connection between said plate a and the plate connected to the forward or outer end of C^2 , and through said latter plate with C^2 and the whole series of bobbins between 25 C^2 and the collecting-brush at the other terminal of the series of brushes m above the neutral line. Under the conditions above supposed, in which the longer insulating-spaces are equal to fifteen degrees, it is sufficient to 30 make the combined width of P^2 and m equal to seventeen degrees. This is accomplished by adding three and one-half degrees to the width of a brush, m , to make brush P^2 , (which is the proportion indicated in the drawings,) and 35 connecting it with the opposite overlapping brush, which is here supposed to overlap four and one-half degrees, or by simply adding to one brush—as, for instance, to the inner terminal brush—eight degrees in width. In order 40 to allow the current to be taken from the two halves of the armature above and below the neutral line $X X$ independently, it is obvious that at and near that line the bobbins for the time being above and below the same 45 shall not be connected. For this purpose the ends of the two terminal collecting-brushes contiguous to one another and above and below the line should be separated by a space greater than that embraced by any pair of 50 contiguous plates a connected to the outer and inner ends of the same coil and the longer insulating-space between the two plates of the pair. As the space thus covered is equal to 55 $6+6+15=27$ degrees, the arc embraced between points $d d$ should be greater than twenty-seven degrees when the lengths of the conducting and non-conducting spaces are those above given. At the opposite end of the series of 60 brushes m , above line $X X$, a collecting-brush, $N^2 m$, is indicated, in all substantial respects similar to $P^2 m$.

The collecting-brushes for the series m below

the line $X X$ are indicated at $P' m$ and $N' m$. With the direction of current in the armature-bobbins indicated by the dotted arrows W , 70 brushes $P^2 m$ and $P' m$ will both collect current of the same polarity—say positive—and the two other brushes, $N' m$ and $N^2 m$, current of the opposite polarity. Under such conditions all that is necessary in order to take all the useful current generated in the machine for tension or high electro motive force is to connect brush $P^2 m$ with brush $N' m$, as indicated, and to make the brushes $P' m$ and $N^2 m$ respectively the positive and negative terminals of the armature-circuit, and connect them, as usual, one to the field-of-force bobbins and the other to a working circuit, or to utilize the current in any other suitable manner. The circuit of the armature coils, starting from brush $N^2 m$, is then, 80 through the series of coils for the time being above the neutral line $X X$ to brush $P^2 m$ to brush $N' m$, through the series of coils for the time being below the neutral line, and out at brush $P' m$. 90

I have described my invention in connection with armatures of the Gramme type only; but it will be understood that it is also applicable to any form of armature in which all or nearly all the coils on the armature are generating 95 useful current at the same time, and in which the coils on each side of the armature can be connected in separate series. In constructing the armature I may employ a ring or a cylinder and wind it with separate coils of insulated 100 wire in any of the ways well known in the art. The ring or cylinder may be continuous, or may be constructed of separate pieces insulated from one another and suitably mounted on a spider-frame, in the manner described in my application for improvements in dynamo-electric machines filed October 21, 1881, or in any other suitable manner.

I have described the position of the brushes that effect the connection in one series of the 110 coils on each side of the neutral line as being at the ends of the cylindrical armature; but it will be understood that this is only one of the means that may be employed for the purpose of carrying out that part of my invention 115 that relates to the connection of the coils on each side of the neutral line in one series. It is unessential what particular arrangements of parts are employed for this purpose, or what particular mechanical constructions are used 120 for completing the circuit between the ends of contiguous bobbins as the armature revolves. Other means besides those herein shown may be employed without departing from the spirit of the invention, and many other devices will 125 readily suggest themselves to those skilled in the art. I therefore wish it to be understood that my invention consists broadly in bringing the contiguous ends of adjoining bobbins to the separate insulated plates, contacts, or points 130 of a circuit-closing apparatus, and in completing the circuit between the free terminals or contiguous ends by suitable means as the armature revolves, the construction being such

that at or near the neutral points where the circuit-closing apparatus does not act the circuit between the contiguous bobbins is left open.

5 The armature, constructed and connected as before described, is mounted on suitable bearings, so as to be capable of rotation between the pole-pieces of the field-magnets. I may employ for this purpose pole-pieces of 10 any convenient shape that are suitably arranged for use with this character of armature. When the machine is designed to furnish powerful currents of very high electro-motive force, I sometimes prefer to employ the 15 magnet-frame shown in connection with Fig. 4. To the base-plate T T, of any suitable material, are attached the heavy uprights D D and D' D', of cast-iron. To these uprights are securely fastened, by bolts or otherwise, the 20 field-magnets M M M M M M. The coils of insulated wire on the magnets are wound so as to produce the poles N N N N N N and S S, &c., as shown—that is to say, the polarity of the magnets that face each other end to 25 end is the same. The magnets are provided with curved pole-pieces N N and S S, &c., shaped to conform to the circular outline of the armature that revolves between them. Spaces O'' O'' O'' are left between the opposite 30 pole-pieces, so as to provide for the proper ventilation of the armature. This end is also secured by the spaces left between the contiguous magnet-coils. Spaces O' O' in the sides D D and D' D' still further aid ventilation. 35 For the same purpose openings are provided at O''' O''' O''', extending from the plates D D and D' D', through the cores of the field-magnets, to any suitable portion of the inner surfaces of the pole-pieces N N and S S. Openings O'' O'', &c., are also provided, extending vertically downward completely through the pole-pieces. These openings are shown cutting the former at right angles. Besides the advantages secured by this construction of the field-magnets in thoroughly ventilating the armature, it affords ease in the construction of very large machines from the aid afforded in handling and winding the separate coils of the field-magnets, and also aids considerably in effecting a more thorough insulation of the coils—a thing very necessary in machines developing currents of very high electro-motive force.

What I claim as my invention is—

1. The combination, substantially as described, with an armature provided with a series of independent bobbins or helices, each having two free ends, of circuit-closing devices for completing the circuit as the armature revolves between the positive and negative 60 free ends of contiguous helices, said circuit-closing devices being applied in the manner described, so as to complete the circuit only between these bobbins which are passing from one neutral point to the other, thus leaving the terminals of the bobbins, which are for the time being at the latter points, disconnected.

2. The combination, with the coils or helices of a ring-armature, of a commutator provided with independent pairs of insulated strips or 70 pieces, circuit-connections from each pair to the opposite ends of contiguous helices upon the armature, independent insulated circuit-closing plates or springs, arranged, as described, so as close the circuit between each 75 pair of insulated commutator-strips, and an extended terminal collecting plate, brush, or spring, as and for the purpose described.

3. The combination, with the bobbins of a ring-armature, of a commutator-cylinder provided with independent pairs of insulated strips or pieces, arranged as described, circuit-connections from each pair to the opposite ends of contiguous bobbins, two sets of insulated circuit-closing plates or springs upon 85 each side of the neutral line, for closing the circuit between the opposite ends of contiguous bobbins as the armature revolves, and terminal collecting plates or brushes, arranged as described, to preserve a connection with the 90 same ends of successive bobbins.

4. The combination, substantially as described, of a series of armature helices or bobbins, separate insulated commutator strips or pieces, arranged in pairs, as described, with 95 the space between the two strips of any one pair less than that between the contiguous strips of adjoining pairs, independent electrical connections from the strips of each pair to the opposite ends of contiguous helices, and 100 circuit-closing plates, brushes, or springs adapted to connect the strips of each pair, but to leave the connection between the contiguous strips of adjoining pairs constantly open.

5. The combination, substantially as described, of a commutator-cylinder provided with separate insulated strips or pieces, arranged in pairs, as described, with the space between the strips of each pair less than the space between independent pairs, and two 110 sets of circuit-closing springs, brushes, or plates for closing the circuit between each pair of strips, said springs or plates being arranged, as described, with the plates of one set breaking joint with the plates or springs of the 115 other set.

6. The combination, substantially as described, of a commutator-cylinder provided with pairs of insulated plates or strips, arranged as described, a set of insulated circuit-closing 120 springs, brushes, or plates bearing upon the cylinder and adapted to close the circuit between each pair of plates, but to leave the circuit open between contiguous pairs, and an extended terminal connecting plate or spring, 125 as and for the purpose described.

7. The combination, with a series of armature helices or bobbins, of separate insulated commutator strips or pieces, to which the ends of the helices are separately connected, said 130 strips or pieces being spaced, as described, so that the space occupied by the strips or pieces to which the ends of any one helix are connected is greater than that occupied by the

two contiguous strips or pieces to which the opposite ends of contiguous helices are connected.

8. A commutator-cylinder for a magneto-electric or dynamo-electric machine, provided with consecutive pairs of insulated strips or pieces, spaced, as described, so that the distance between the two strips of each pair is less than that between the strip of one pair and the next succeeding strip of a contiguous pair.

9. The combination of the base-plate, the vertical plates, having vertical slots between the points at which the field-magnets are se-

cured, and the series of field-magnets, bolted 15 to the vertical plates and separated from one another by free air-spaces, substantially as and for the purpose described.

10. The combination, substantially as described, of the hollow field-of-force magnet- 20 cores and the pole-pieces or extensions, provided with openings extending therethrough at right angles to the hollow cores.
